(57) **CLAIM**

The ornamental design for a fender hook, as shown and described.

DESCRIPTION

FIG. 1 is a front, side perspective view of a fender hook showing my new design;
 FIG. 2 is a right side elevational view thereof;
 FIG. 3 is a rear elevational view thereof;
 FIG. 4 is a left side elevational view thereof;
 FIG. 5 is a front elevational view thereof;
 FIG. 6 is a top plan view thereof;
 FIG. 7 is a bottom plan view thereof; and,
 FIG. 8 is a front, side perspective view of the fender hook of FIG. 1 in a folded configuration.
